UNITED STATES PATENT OFFICE.

WILLIAM A. PRATT, OF BAYONNE, NEW JERSEY.

FLUSHING VALVE.

Application filed November 5, 1925. Serial No. 67,091.

This invention relates to flushing valves and is an improvement over my Patent No. 555,755, issued Sept. 29, 1925, the object of the invention being to provide a simplified structure which may be readily assembled and disassembled.

Another object of the invention is to provide a flushing valve wherein there is provided what may be termed an inner and outer head.

A further object of the invention is to provide a flushing valve wherein the parts are so formed that the operating lever may be shifted around the casing of any desired point and thus eliminate the making of different forms of inlet members.

In the accompanying drawing—

Figure 1 is a longitudinal vertical section through a valve disclosing an embodiment of the invention.

Figure 2 is a view similar to Figure 1 but showing the parts in their operated position with the valve flushing.

Figure 3 is a sectional view through Figure 1 on line 3—3.

Figure 4 is a sectional view through Figure 2 on line 4—4.

Referring to the accompanying drawing by numerals, 1 indicates a casing provided with an inlet 2 near the bottom and an outlet 3 at the bottom. The outlet structure 3 includes a valve seat 4 adapted to receive the washer 5 of the valve member 6. The valve member 6 is provided with a short stem 7 and what may be termed a lifting plate 8. This lifting plate is provided with a suitable washer 9 held in place by a plate 10 and screw 11. The screw 11 extends preferably loosely through the valve 6 and is screwed into the deflector 12. This deflector is provided with a deflecting surface 13 set to deflect the flow of water in inlet 2 so as to pass out the outlet 15 and is also provided with a depending portion 14 which overlaps the outlet opening 15 of the overflow of passage-way 16. The deflector 12 is provided with a groove 17 which accommodates a short key 18 preferably integral with the casing 1. This arrangement prevents the rotation of the deflector 12 and, consequently, continually holds the inclined surface 13 in proper position and also holds the extension 14 so that it will continually cover the outlet 15. This is desirable as a back pressure of water passing out through the outlet 3 might back up into the passage-way 16 and thereby

interfere with the proper operation of the entire device. However, a reverse is true by reason of the extension 14. As the water passes the deflecting surface 13 and moves downwardly, it will produce a suction or rarefaction at the outlet 15 so that passage-way 16 can function in a very efficient manner. The passage-way 16 is formed in a suitable enlargement 19 integral with the casing 1 while a passage-way 20 is formed in the enlargement 21 integral with the casing 1. The bypass or pressure passage-way 20 discharges into an annular groove 22 and from this groove the water passes through 70 an aperture 23 into the chamber 24. The groove 22 is made in the inner head 25, which inner head is covered and protected by the outer head 26; said outer head in effect being a casing and a protecting structure. 75 The inner head 25 is screwed into the casing 1 as shown in Figure 1 and at the lower end clamps a strainer 27 in position against a division plate 28, which division plate is provided with a very small dent 29 whereby 80 water may pass into and from the chamber 30. The plate 28 is also provided with an aperture for loosely accommodating the pin 31, which pin is preferably provided with an enlarged head so that the same may readily co-act with the lower end of the plunger 32. This plunger is threaded at the lower end and has screwed thereon a member 33 which acts as an auxiliary valve and carries a washer 34 normally engaging the 90 shoulder 35 for closing the passage-way 36. The passage-way 36 opens into a chamber 37 having a number of radial holes or apertures 38 discharging into the interior of the shell 39. The shell 39 is provided with a 95 number of openings 40 so that water discharged through passage-way 38 into this shell will readily find its way into contact with the casing 26 and from thence into the passage-way 16 and finally out through the 100 outlet 15.

From Figure 3, it will be noted that the inner head 25 is provided with a bore 41 for accommodating the piston 33 and this bore is provided with side notches 42 so that when the parts are in the position shown in Figure 2 the water may pass from chamber 30 through the vent 29, through passage-ways 42 and from thence through the passage-way 36 so as to be readily exhausted. The shell 39 is made in two parts as shown in Figure 4 whereby the inner annular flange 43 may

be readily fitted into the annular groove 44 of the inner head 25. At the upper end a threaded section 45 is formed on the shell 39 whereby the cap 46 may be screwed thereon and when the cap is properly screwed into position, it will pull upwardly on the shell 39 and press downwardly on the outer head or casing 26 so as to lock the same in position and also effect a tight connection between the same and casing 1. In order to prevent the parts of shell 39 from moving toward each other at the upper end, a ring 47 is fitted within the threaded portion 45, said ring preferably having an overhanging flange overhanging the threaded section 45. The plunger 32 is provided with an offset section 48 having a slot 49 therein, said slot being adapted to accommodate a pin 50, said pin being provided with a suitable nut 51 for holding the same in place. The pin 50 extends loosely through one end of a link 52 and the opposite end extends through a wrist pin 53 preferably formed integral with the enlargement 54 of shaft 55. The shaft 55 is connected in any suitable manner with a hand lever 56. When the parts are as shown in Figure 1, the valve is closed and when it is desired to open the same lever 56 is swung in either direction to a position substantially at right angles to the position shown in Figure 1 whereupon the parts will assume the position shown in Figure 2. As soon as this takes place, piston 33 is positioned over the aperture 23 and, consequently, no water can flow from the by-pass or passage-way 21. Also, the piston 34 will displace the water already in the chamber 24 and cause this water to flow upwardly through the passage-way 36 and finally out through the outlet passage-way 16. Also water in the chamber 30 will slowly pass through the vent 29 and from thence out through the passage-way 16 as just described. The movement of the valve member 6 causes the water to flow from chamber 30 as described, said valve member being moved by the pressure of water from inlet 2 acting on member 8 and later on member 8 and the inclined surface 18. The hand lever 56 may be swung around to any desired position, as for instance, to the position shown in dotted lines in Figure 4.

This is permitted by the fact that the outer head 26 may be freely rotated except when the cap 46 has been screwed down tight. It will thus be seen that by loosening this cap the head 26 and lever 56 may be shifted to a desired position and then cap 46 tightened.

When the parts are in the position shown in Figure 2, the valve is only partly open but will continue to move upwardly until the screw 11 engages the pin 31 and forces the same upwardly and also forces the piston 33 and associated parts upwardly until they again assume the position shown in Figure

1. When this occurs, passage-way 36 is closed and the aperture 23 opened whereupon water under pressure may enter chamber 34 from the by-pass 21. This water gradually passes downwardly through the vent 29 into chamber 30 and, therefore, gradually forces the valve member 6 downwardly until it again assumes its closed position as shown in Figure 1. It will thus be seen that the action of the lever or handle 56 merely shifts certain parts in the valve structure so that the water itself will act both to open the valve 6 and to close the same. The vent 29 may be of any desired size and the pin 31 may be varied in length by removing the same and substituting a new pin either longer or shorter. The longer the pin 31 the less period of opening will be provided.

What I claim is:

1. An automatic valve, comprising a housing having an inlet opening and an outlet opening, a valve for controlling the outlet opening, said valve being formed with an inclined face and a depending extension at one end of the inclined face, said valve being also formed with communicating chambers above the valve, the upper chamber having a passage-way leading from the upper end, a by-pass leading from the inlet into the lower part of said upper chamber, an overflow conduit leading from the outlet passage-way of said upper chamber to the outlet opening of the housing, said conduit discharging into said outlet opening against the extension of said valve and on the opposite side to said inclined face, a valve in said upper chamber adapted to seat in such a manner as to close the outlet passage-way therefrom when the valve is in one position and to close the by-pass when in another position, and means for operating the valve.

2. In an automatic valve of the character described, a casing provided with an inlet opening and an outlet opening, a valve member for controlling said outlet opening, said valve member having an actuating disk, means for clamping a washer on said disk, said washer snugly fitting the bore of said casing, a dividing plate arranged in the casing and spaced normally from the valve member whereby a control chamber is provided, an inner head screwed into the upper part of said casing formed with a central opening in the upper part presenting an upper chamber, said dividing plate having a vent extending therethrough, a piston arranged in said upper chamber, manually actuated means for shifting said piston, said inner head having an annular groove, an aperture extending from said annular groove into said upper chamber, means on said casing presenting a passage-way from said inlet opening through said annular groove whereby water under pressure may enter said upper chamber, said head having

a passage-way extending from the lower part of the upper chamber to a point exteriorly of said inner head, a piston normally closing said passage-way, means forming an outlet passage-way from a point exteriorly of said inner head to said outlet opening, and a removable pin mounted in said dividing plate, said pin extending into the first mentioned chamber and acting to raise said piston when said valve has been moved its full stroke upwardly.

3. In an automatic flushing valve, a casing provided with inlet and outlet openings near the bottom, a valve member for controlling said outlet opening, means connected with the upper part of the casing for controlling said valve, said means including an inner head, a reciprocating member associated with said inner head, a rock shaft operatively connected with said reciprocating member for operating the same, a handle secured to said rock shaft, an outer head fitted onto said casing and acting as a journal member for said rock shaft, said outer head being capable of rotation in a plane at right angles to the axis of the casing whereby said handle may be positioned at any point around the casing, a shell arranged in said outer head and rotatably connected with

said inner head and a cap threaded on said shell, said cap being formed to bear against said outer head when the cap is screwed down whereby said outer head will be pressed against said casing and thereby held against rotation.

4. In an automatic flushing valve, a casing provided with inlet and outlet openings near the bottom, a valve member for controlling said outlet opening, means connected with the upper part of the casing for controlling said valve, said means including a handle arranged exteriorly of the casing, a shaft rigidly secured to the handle, an outer head rotatably mounted on the casing, said outer head being capable of rotation in a plane at right angles to the axis of the casing, said outer head being formed with an enlargement acting as a bearing for said shaft, a shell mounted in said head and fixed at the lower end so that it may be rotated but not moved longitudinally of the outer head, and a cap screwed onto said shell, said cap having a portion positioned to press against the upper end of said outer head for pressing the outer head against said casing whereby the outer head is locked against independent movement.

WILLIAM A. PRATT.
